UNITED STATES PATENT OFFICE.

CLIFFORD C. BRADBURY, OF MOUNT VERNON, NEW YORK, ASSIGNOR TO WESTERN ELECTRIC COMPANY, OF NEW YORK, N. Y., A CORPORATION OF ILLINOIS.

OVERFLOW TRUNKING SYSTEM.

1,161,602.

Specification of Letters Patent. Patented Nov. 23, 1915.

Application filed July 25, 1914. Serial No. 853,103.

To all whom it may concern:

Be it known that I, CLIFFORD C. BRADBURY, a citizen of the United States, residing at Mount Vernon, in the county of Westchester and State of New York, have invented a certain new and useful Improvement in Overflow Trunking Systems, of which the following is a full, clear, concise, and exact description.

10 This invention relates to overflow trunking systems for automatic telephone exchanges.

Experience has shown that whereas a group of subscribers who originate on their lines a certain average number of calls per hour require a certain number of trunks to accommodate the simultaneous calls arising from this group of subscribers, a larger group of subscribers originating an average 20 of twice as many calls per hour will require considerably less than twice as many trunks to accommodate the simultaneous calls from the larger group. Likewise, a group of subscribers originating an average of 3, 4, 5, ..., n times as many calls per hour as the small group will require in each case considerably less than 3, 4, 5, ..., n times the number of trunks required by the small group to accommodate the simultaneous calls. The arrangement of lines, therefore, which would be ideal, would be one in which all of the subscribers' lines entering the exchange constitute a single group, each line having direct access to every secondary switch of the 30 exchange, and any line having access to the last idle secondary switch of the exchange when all other secondary switches are in use. When the number of lines entering the exchange is large, and the number of required 40 secondary switches consequently large, such an ideal arrangement becomes impracticable from a commercial standpoint on account of the cumbersomeness of the apparatus required.

45 It is the object of the present invention to provide a system of lines and secondary switches by means of which the above pointed out ideal arrangement is approached with apparatus which permits the subscribers' lines to be arranged in small groups in a manner which has proven economical in practice.

The method of carrying out my invention is illustrated in the accompanying drawings, 55 Figures 1 and 2. The various circles 6 rep-

resent subscribers' stations or other sources for originating calls. The arcs of circles 7 and 10 with their associated arms represent respectively primary and overflow switches for distributing calls to any one of the trunk 60 circuits extending either to the secondary switches 9 represented in the drawing by small rectangles, or to other overflow switches 10. The switches 7 and 10 are of any well known type, by means of which 65 connection is automatically established with the first idle trunk. Illustrations of these are numerous in the art of automatic telephony, and no description of any specific type of switch is considered necessary for the 70 purposes of this specification.

The primary switches, of which there is one for each subscriber's line, are arranged in groups designated as the 1st, 2nd, 3rd, 4th, 5th, 6th, 7th and so on to the n th groups, 75 each group comprising approximately 100 subscribers' lines. There may be any desired number of these groups, the n th group bearing the same relation to the 1st, 2nd, 3rd and 4th groups as each group bears to 80 the four groups following it, so that all groups taken together form a cycle, all groups of which bear similar relation to other succeeding groups in the cycle. Each of these groups serves subscribers' lines or 85 other sources of originating calls sufficient in number to originate, except under abnormal circumstances, calls requiring a maximum of ten simultaneous connections. Each primary switch of each group has multiplied to it six trunks extending to six different secondary switches 9, and in addition thereto each primary switch of each group has multiplied to it four trunks extending to 90 four auxiliary or overflow switches 10, having access respectively to the trunks of each of four succeeding groups. With this arrangement each group of originating lines has access to six secondary switches of its own particular group, and in addition thereto, through its four additional trunk lines and four overflow switches, has access to all of the secondary switches of the four succeeding groups and through the last four trunks of each of these groups to the 95 secondary switches of other groups, and so on through all of the groups, including the n th group. Thus, any line may, under proper conditions, connect with any secondary switch of the exchange.

While all of the lines of the exchange have access only to $(6n)$ secondary switches, it does not follow that in order for all of these secondary switches to be used simultaneously the groups must originate six calls to a group; for example, the first group may originate ten simultaneous calls which would use up all of its own secondary switches and four of the trunks extending to overflow switches of other groups. Under favorable conditions the second, or any other one group shown, may at the same time originate any number of calls up to nine, and the 6th group, or any other group beyond that, 15 may again originate ten calls. This arrangement permits a large variation in the number of calls originating from each group without, at any time, depriving any group of the number of accessible secondary 20 switches which experience shows are required to satisfactorily take care of the traffic which is liable to arise in that group.

An additional feature of my invention prevents the primary switches, of a particular group, from unnecessarily establishing a connection with an idle overflow switch in another group when all the trunks serving this overflow switch are busy. This prevents an unnecessary tying up of inter-switch trunks when no connection could be established even though an idle overflow switch were found. For this purpose each of the overflow switches is provided with a normal contact 11 and an off-normal contact 12. The secondary switches are each equipped with two off-normal contacts 13 and 14. The four normal contacts 11 of each group are connected in parallel and are then connected in series with the six off-normal contacts 13 of the same group, and the four off-normal contacts 12 of the first, second, third and fourth overflow switches respectively of the first, second, third and fourth succeeding groups. The movable element of the last off-normal contact 12 is wired to ground or test potential.

The off-normal contacts 14 of all of the secondary switches are connected in series in a single circuit terminating in a grounded battery. The other end of this circuit is connected in parallel through relays 15, one for each group of switches, to the ground terminal of the battery. The armatures of the relays 15 are wired to ground, or test potential, and the make contacts are wired in parallel to the normal contacts of the overflow switches 10 of the particular group associated with each relay. The manner in which these circuits prevent the unnecessary tying up of interswitch trunks will now be illustrated. Whenever the number of simultaneous calls originated in any group is equal to the determined maximum number of simultaneous calls allowed per group, ten 65 per group in the system illustrated, all the

trunks to the secondary switches directly available for this group as well as the trunks leading to the overflow switches which serve this group directly will be busy. In this case all the trunk outlets from such a group will be busy, and it is therefore important that none of the overflow switches of any of the other groups shall select the trunks leading to the overflow switches of the busy group. Such a connection would prevent the call from going to a group in which an idle trunk could be found and would also cause one of the switches of the busy group to continue to unnecessarily hunt over the busy trunk terminals of this group. Hence whenever all of the trunks leading to the secondary and overflow switches of any group are busy, a busy potential should be maintained on the normal contacts of the overflow switches of the busy group. The method by which this is accomplished can be illustrated to the best advantage by assuming a concrete condition. Thus, if all of the trunks extending from the first group are busy, a circuit will be established from the ground at the off-normal contact 12 of the last overflow switch of the 5th group, to and through this off-normal contact and the off-normal contacts 12 of the third, second, and first overflow switches of the fourth, 3rd and second groups, respectively, through the off-normal contacts 13 of the secondary switches of the first group and then to the normal contacts 11 of the overflow switches of the first group in parallel, establishing the busy condition on all of the trunks leading to these switches. Thus the last overflow trunk in the 5th group, the third overflow trunk in the sixth group, the second overflow trunk in the seventh group and the first overflow trunk in the n th group will be connected to the busy potential. The switches in these groups will therefore not select a trunk to the first group until a trunk outlet from the first group is available. At the moment a trunk of the first group becomes available, by reason of the return to normal of one of the switches of the first group, the established busy circuit connected to the overflow switch normal contacts 11 of the first group will be interrupted at one of the off-normal contacts 13 or 12 of the secondary or overflow switches serving the group.

An originating call in any group will never proceed beyond its individual primary switch unless there is an available secondary switch in its own or one of the other groups and in the latter case a circuit through idle overflow switches of the groups leading the idle secondary switch must also be available. This can be described to the best advantage by way of illustration. Thus, summing conditions in which each group with the exception of the n th group has or

- nated six calls and that the n th group has originated five calls. Under these conditions, all the available secondary switches with the exception of the last switch in the n th group will be busy and none of the overflow or auxiliary switches will be in use. With these conditions prevailing, a call originating in the first group would take the following course: The primary switch associated with the calling line would hunt and select the trunk leading to the first overflow switch in the second group, which in turn would hunt and select the first overflow switch in the third group and this process would continue to the n th group. The overflow switch selected in the n th group would then connect the only available idle secondary switch in the system to the calling subscriber in the first group.
- Assuming now a condition in which a call is originated in the first group when all the secondary switches in the system are busy, and at which time either no overflow switches or only a part of the overflow switches are busy. This condition would arise either when each group originates six calls, thus utilizing every available secondary switch in the system for calls, six in number, originating in each group, or when the total number of calls equals the number of secondary switches and are distributed from the various groups in such a manner that the overflow trunks are not exhausted. A condition of this kind may occasionally occur and is described to show that with the severest kind of traffic conditions there will be no unnecessary tying up of trunks, but on the contrary, the primary switch associated with the calling subscriber will be the only switch which becomes operative. This condition will continue until one of the secondary switches in the system is released, at which time this switch will be selected as previously explained.
- Having assumed that all the secondary switches are busy, it then follows that the series circuit through the off-normal contacts 14 is closed. The now closed off-normal contacts 14 complete a circuit through all the relays 15 in parallel. The operation of each one of these relays connects the busy potential with the normal contacts 11 of the overflow switches of the group associated with each relay. This places the busy test potential on the normal contacts 11 of all the auxiliary switches in the system not actually in use, and as all the secondary switches in the system are also busy, every switch contact in the system is connected to the busy potential. Under these circumstances the wiper of any calling subscriber's primary switch finds all of the switch contacts busy and may be arranged to continue to hunt or not to start hunting, or to give the subscriber a busy test, until one of the secondary
- switches is released, thereby opening the series circuit through its off-normal contacts 14, which will remove the busy potential from the normal contacts 11 of all of the overflow switches not actually in use. The call will then proceed through the idle overflow switches until the released secondary switch is selected.
- Obviously this invention is not limited to the specific embodiment herein shown and described, but is capable of many variations and applications without departing from its spirit and scope.
- What is claimed is:
1. In a trunking system, the combination with incoming and outgoing circuits, of automatic means for establishing connection between an incoming circuit and an idle outgoing circuit, said outgoing circuits being of two classes and so arranged that the circuits of one class will all be selected before any of the circuits of the other class are selected; a selector switch for each of the outgoing circuits of the preferred class, each of the other outgoing circuits appearing as an incoming circuit in another group and at said group having access to other outgoing circuits of two classes similar to the outgoing circuits of the first group.
  2. In an automatic telephone system, subscribers' lines arranged in groups, primary switches for said subscribers' lines, trunk lines terminating in said primary switches, secondary switches associated with a part of said trunk lines, overflow switches associated with the remainder of said trunk lines, said overflow switches in each group having access either directly or through other overflow switches to the secondary switches of any group.
  3. In an automatic telephone system, the combination with subscribers' lines arranged in groups, a primary switch for each subscriber's line, secondary and overflow switches associated with each group, means for connecting a calling line in any group with the first idle secondary switch in that group, or if the secondary switches of that group are busy with the first accessible idle overflow switch of one of the other groups, means to connect said overflow switch with any secondary switch of the selected group, or if the secondary switches of that group are busy with an idle overflow switch of one of the other groups, and means to connect the overflow switches of each selected group, with the secondary switches of that group, or if the secondary switches of that group are busy with an idle overflow switch of one of the other groups.
  4. In an overflow trunking system, originating lines, primary, secondary and overflow switches, all arranged in groups, trunks multiplied to the primary and overflow switches of each group and terminating in

the secondary switches of that group, other trunks multiplied through the primary and overflow switches of each group and terminating in similar overflow switches of other groups, whereby an originating line 5 may be connected through one of the trunks of its group to a secondary switch of its group, if one is idle, or to a selectable overflow switch of some succeeding group, and 10 through the selected overflow switch to a secondary switch of the selected group, if one is idle, or another selectable overflow switch of some succeeding group, and through this or some succeeding overflow 15 switch to the first available idle secondary switch.

5. In an overflow trunking system, the combination with subscribers' lines arranged in groups, of primary switches for 20 said subscribers' lines, trunk lines terminating in said primary switches, secondary switches associated with a part of said trunk lines and overflow switches associated with the remainder of said trunk lines, said primary 25 switches serving to connect a subscriber in any group with the first idle secondary switch of that group, or with an overflow switch of another group if the secondary switches are busy and said selected 30 overflow switch serving to connect the subscriber with the first idle overflow switch of one of the succeeding groups provided the secondary switches of the selected group are busy and an idle trunk by way of overflow 35 switches to the group containing an idle secondary switch is available, and means to prevent a calling line from being connected with an overflow switch when there is no idle secondary switch.

40 6. In an overflow trunking system, the combination with subscribers' lines arranged in groups, of primary switches for said subscribers' lines, overflow switches in each group selectable by the primary and overflow 45 switches of other groups, secondary switches accessible to the primary and overflow switches of all groups, and means to prevent a subscriber's line from being connected with an overflow switch when all the 50 secondary switches in the system are busy.

7. In an overflow trunking system, the combination with subscribers' lines arranged in groups, of primary switches for said subscribers' lines, secondary and overflow 55 switches associated with the primary switches and means to cause the overflow switches in all of the groups to test busy whenever the secondary switches in all of the groups are busy.

60 8. In an overflow trunking system, the combination with subscribers' lines arranged in groups, of primary switches for said subscribers' lines, secondary and overflow switches associated with the primary

switches, means to cause the overflow 65 switches in all the groups to test busy whenever the secondary switches in all the groups are busy, and to remove said busy test whenever one of said secondary switches is released.

9. In an overflow trunking system, the combination with subscribers' lines arranged in groups, of primary switches for said subscribers' lines, trunk lines terminating in said primary switches, secondary switches 75 associated with a part of said trunk lines and overflow switches associated with the remainder of said trunk lines, said primary switches serving to select the first idle secondary switch of that group or an overflow 80 switch of another group if the secondary switches are busy, said selected overflow switch serving to select the first idle overflow switch of one of the succeeding groups provided the secondary switches of the selected group are busy, and means to maintain a busy potential on the trunks terminating in the overflow switches of any group whenever all the trunks extending from said group are busy.

90 10. In an overflow trunking system, the combination with subscribers' lines arranged in groups, of primary switches for said subscribers' lines, trunk lines terminating in said primary switches, secondary switches 95 for each group and overflow switches of other groups connected to the trunk lines of each group, and means to maintain a busy potential on all of the trunk lines of a group when the secondary switches of that 100 group are busy and there is no available trunk from any of the overflow switches in other groups to which the overflow trunks of that group extend.

11. In an overflow trunking system, the 105 combination with subscribers' lines arranged in groups, of primary switches for said subscribers' lines, trunk lines terminating in said primary switches, secondary switches for each group and overflow switches of 110 other groups associated with the trunk lines of each group, and means to delay the progress of interswitch trunking at the originating primary switch unless there is an available trunk to an idle secondary switch 115 in one of the groups of the system.

12. In a trunking system, the combination with a group of originating lines, of a plurality of trunk line groups, automatic means for establishing connections between an 120 originating line and idle ones of the trunk lines of its group, secondary switches connected with certain ones of said trunk lines, the other of said trunk lines extending as originating lines to other groups of trunk lines and there terminating in automatic means for establishing connection between 125 said trunks of the first group and idle trunks

of the other groups, a part of the trunks of the other groups likewise terminating in secondary switches.

13. In a trunking system, a plurality of originating lines, two groups of trunk lines, similar automatic secondary switches for a part of the trunk lines of each group, one of the trunk lines of one group terminating as an originating line in the other group, and automatic means to connect originating lines with idle trunks.

14. In a trunking system, the combination with a plurality of originating lines, of a movable contact wiper for each line, a plurality of stationary trunk contacts for engagement by said wipers, a plurality of overflow trunk circuits, a movable contact wiper for each

overflow trunk circuit, a plurality of stationary trunk contacts for engagement by said wipers, said stationary contacts being 20 multiply connected to the stationary trunk contacts before mentioned, secondary switches connected to certain of said multiplied trunk contacts, other movable contacts connected to the remainder of said multiplied trunk contacts, and other multiplied trunk contacts accessible to said latter movable contacts.

In witness whereof, I hereunto subscribe my name this 23rd day of July, A. D. 1914.

CLIFFORD C. BRADBURY.
